STRUCTURAL MEMBER

William F. Davis, Mound City, Ill., assignor to
Sears, Roebuck and Co., Chicago, Ill., a corpora-
tion of New York

Application November 12, 1936, Serial No. 110,440

10 Claims. (Cl. 108—23)

My invention relates to structural members and has to do more particularly with a composite or "lattice" truss so designed as to be especially adapted for wood fabrication.

5 A particular object of my invention is to provide a truss of exceptional strength although of moderate cost.

10 A further object is to provide such a device which may be made wholly out of wood and which will be simple in design and inexpensive to fabricate, and especially adaptable as a roof support.

Referring now to the drawings forming a part of this specification and illustrating a preferred embodiment of my invention:

15 Fig. 1 is a side elevational view of a truss embodying my invention;

Fig. 2 is a fragmentary sectional view on an enlarged scale taken substantially along the line 2—2 of Fig. 1;

20 Fig. 3 is a sectional view taken substantially along the line 3—3 of Fig. 1;

Fig. 4 is an end elevation of the same;

Fig. 5 is a sectional view taken substantially along the line 5—5 of Fig. 1; and

25 Figs. 6, 7, and 8 are fragmentary elevational views of elements forming part of the composite truss constituting my invention.

Trusses embodying my invention preferably comprise a plurality of skeleton truss members indicated by the numerals 10a, 10b, 10c, and 10d (see Fig. 3). Each of these members just referred to comprises a straight beam 12 and an arcuate beam 15. These beams may be formed of a single length of wood or other suitable material, 30 or of a plurality of lengths. The straight beams 12 are preferably increased in depth at their ends, as indicated at 13. Said increase of depth may be accomplished as shown, by means of separate lengths of material, or by providing integral enlarged end portions in the beams 12. The ends 35 of the beams 12 are joined by the arcuate spans or girders 15, which members likewise may be formed of a single length or of several lengths of material.

40 Secured between two of the skeleton members, say the members 10d and 10c, is a plurality of oblique struts 17 (Fig. 6). The spaces between said struts are filled by means of spacing members 18 on both the straight beam 12 and arcuate girder 15. The spacing members 18 as seen best in Fig. 2, are preferably equal in thickness to the struts 17.

The struts 17 are preferably disposed at an angle of 45 degrees and it will be seen that I have 45 spaced the struts 17 closer together adjacent the

ends of the structural unit, as seen in Fig. 6, than in the middle. This is for the reason that I have found that the failure of trusses of this type occurs most frequently adjacent the ends.

Secured between the skeleton trusses 10c and 5 10b is a plurality of vertical struts 20. These struts are also spaced closer together adjacent the ends of the truss than in the middle, as seen clearly in Fig. 7, and spacers 21 are preferably provided between said vertical struts 20.

10 Disposed between the skeleton trusses 10a and 10b is a plurality of oblique struts 25 (Fig. 8), these struts being likewise preferably arranged at an angle of 45 degrees and oppositely to struts 17 and spaced closer together adjacent the ends 15 of the truss. Spacers 26 are provided between the ends of the struts 25.

15 At seen best in Fig. 1, the struts are preferably so arranged longitudinally that three struts, i. e., two of the oblique struts extending in opposite 20 directions and an interposed vertical strut, cross each other at various points throughout the length of the truss as, for example, at 28, said crossing points lying in a common line for the major part of the truss length. At these points filler blocks 25 30 are inserted and the struts and blocks are tied together as by means of nails 31 (Fig. 3). Obviously, other securing devices might be used, such as screws, bolts, etc., and such securing devices are used throughout the entire structure for joining the various members.

25 The arcuate portion of the truss is preferably provided with one or more longitudinal tie members 33 which serve to bind the various composite elements of the arch as seen best in Figs. 3 35 and 5.

30 It will be apparent that, although my invention is especially applicable to wood fabrication, it may be used for various other materials, such as, for example, steel, in which case joining may 40 be accomplished by welding or other suitable means.

35 Tests show that structural members embodying my invention withstand much heavier loads before failure than any similar structural members 45 with which I am familiar.

40 Various changes coming within the spirit of my invention may suggest themselves to those skilled in the art, and hence I do not wish to 50 be limited to the specific embodiment shown or uses mentioned except to the extent indicated in the appended claims which are to be interpreted as broadly as the state of the art will permit.

I claim:

1. A structural member comprising a plurality of pairs of skeleton trusses arranged in spaced parallel relation, each truss having a straight portion and an arcuate portion, and a series of struts disposed between each pair of adjacent skeleton trusses, said struts comprising two series of oblique struts extending angularly to each other, and a series of vertical struts, members of the three series crossing at points throughout substantially the entire length of the structural member, and means securing said oblique and vertical struts together at said crossing points.
2. A device as defined in claim 1 wherein each series of oblique struts is disposed at an angle of 45 degrees.
3. A device as defined in claim 1 wherein the struts are more closely spaced adjacent the ends of the structural member than in the middle thereof.
4. A structural member comprising a plurality of pairs of skeleton trusses arranged in spaced parallel relation, each of said trusses comprising a straight member and an arcuate member having their ends joined, a series of struts secured between a pair of said skeleton trusses and arranged at an angle of 45 degrees, another series of struts disposed between another pair of skeleton trusses and perpendicular to said first series of struts, a series of vertical struts disposed between another pair of skeleton trusses and arranged intermediate of said diagonal struts, members of the three series of struts crossing at points throughout substantially the entire length of the structural member, and means securing said struts together at said crossing points.
5. In a device as defined in claim 1, members disposed between the ends of the struts of each series and substantially filling the space therebetween.
6. In a device as defined in claim 4, members disposed between the ends of the struts of each series and substantially filling the space therebetween.
7. A structural member comprising a plurality of pairs of skeleton trusses arranged in spaced parallel relation, each truss having a straight portion and an arcuate portion, and a series of struts disposed between each pair of adjacent skeleton trusses, said struts comprising two series of oblique struts extending angularly to each other, and a series of vertical struts, members of the three series crossing at points throughout substantially the entire length of the structural member, means securing said oblique and vertical

struts together at said crossing points, and a longitudinal tie member having a flat side overlying substantially the full length of and secured to the outer edges of said arcuate portions.

8. A structural member comprising a plurality of pairs of skeleton trusses arranged in spaced parallel relation, each truss having a straight portion and an arcuate portion, and a series of struts disposed between each pair of adjacent skeleton trusses, said struts comprising two series of oblique struts extending angularly to each other, and a series of vertical struts, members of the three series crossing at points throughout substantially the entire length of the structural member, and means securing said oblique and vertical struts together at said crossing points, the ends of said straight portion being of greater depth than and projecting below the lower longitudinal edge of the intermediate part of said straight portion.

9. A structural member comprising a plurality of pairs of skeleton trusses arranged in spaced parallel relation, each truss having a straight portion and an arcuate portion, and a series of struts disposed between each pair of adjacent skeleton trusses, said struts comprising two series of oblique struts extending angularly to each other, and a series of vertical struts, members of the three series crossing at points throughout substantially the entire length of the structural member, and means securing said oblique and vertical struts together at said crossing points, said struts being more closely spaced adjacent the ends of the structural member than in the middle thereof, said points of the relatively remotely spaced struts lying in a straight line parallel to said straight portion.

10. A structural member comprising a plurality of pairs of skeleton trusses arranged in spaced parallel relation, each truss having a straight portion and an arcuate portion, and a series of struts disposed between each pair of adjacent skeleton trusses, said struts comprising two series of oblique struts extending angularly to each other, and a series of vertical struts, members of the three series crossing at points throughout substantially the entire length of the structural member, and means securing said oblique and vertical struts together at said crossing points, said struts being more closely spaced adjacent the ends of the structural member than in the middle thereof, said series of struts constituting the sole connecting means in the space between said portions.

WILLIAM F. DAVIS.
